UNITED STATES PATENT OFFICE.

ROBERT WORTLEY CLOUGH PALMER, OF LONDON, ENGLAND.

BUTTON-LIKE DRESS-FASTENING.

No. 896,041.

Specification of Letters Patent.

Patented Aug. 11, 1908.

Application filed September 3, 1907. Serial No. 391,197.

To all whom it may concern:

Be it known that I, ROBERT WORTLEY CLOUGH PALMER, a subject of the King of Great Britain, residing at London, England, have invented new and useful Improvements in Button-Like Dress-Fastenings, of which the following is a specification.

This invention consists in the improvements hereinafter described in the connection 10 of the heads to the other parts of button like dress fastenings such as sleeve links and collar studs for the purpose of facilitating insertion thereof into button holes.

According to the said invention radial or 15 approximately radial recesses are formed in the backs or innersides of the heads of the said articles extending from the center to the periphery and in the case of sleeve links each end of the coupling part has the form of a 20 spherical knob which knobs are respectively engaged with the heads at the junction of the said recesses in a manner essentially similar to the engagement of the parts of a ball and socket joint.

25 In the case of a collar stud the head and stem part are formed separately and the stem part has a knob at its end by which it is connected to the head as described with reference to sleeve links.

30 A sleeve link and a collar stud made according to this invention are illustrated on the accompanying sheet of drawings herein-after described.

Figures 1 and 2 of the said drawings are 35 respectively a back view and an edge view of the link with the heads side to side. Figs. 3 and 4 are similar views with the heads end to end and Fig. 5 is a separate view of the coupling part. Figs. 6, 7 and 8 are side 40 views of the collar stud. In Fig. 6 the parts are represented in the relative positions which they occupy when the stud is in wear and in Figs. 7 and 8 in their relative positions for passing the head through a button hole 45 the head being shown in edge view and underface view respectively in the said Figs. 7 and 8. Fig. 9 is a section taken on the line A A Fig. 1, Fig. 10 is a section taken on the line B B Fig. 8 and Figs. 11 and 12 are separate 50 views of modified forms of the coupling part of a sleeve link. The said Figs. 9 and 10 are drawn to double the scale of the other figures of the drawings.

In the following description of the said 55 drawings the parts thereof are referred to by the letters marked thereon the same letters

of reference being used to indicate the same parts in the several figures of each of the aforesaid articles.

Referring to Figs. 1 to 5 and 9 *a a* are the 60 head parts of the link *b b* are the recesses in the backs or innersides thereof at the junction of which recesses are formed sockets with which the spherical knobs *c c* at the ends of the coupling part *c** are so engaged as to 65 admit of free swiveling motion. The said sockets are formed partly in the plate portions of the head parts *a a* as shown in Fig. 9 and partly by the upstanding overhanging 70 converging extremities of the portions between the recesses *b b*. The said recesses extend from the center to the periphery of each of the head parts and the bottoms of the recesses are parallel to the general plane of each of those parts and distant below the 75 centers of the knobs *c c* one-half the diameter of the stem portion of the coupling part *c** and the width of each of the said recesses *b b* at the end next the said knobs must be at least equal to the diameter of the said stem 80 portion of the coupling part. The said recesses thus permit of the coupling part *c** being turned down into any one of them parallel to the head part in which it is formed 85 their function being to receive the said coupling part when the parts are brought into line as illustrated in Figs. 1 to 4 and also to allow relative angular movement of the parts *a* and *c** through 180° except at the mere 90 points of convergence of the parts between the recesses.

When the parts are in the relative positions illustrated in Figs. 3 and 4 engagement of the article with the button holes of a cuff can be effected with great facility owing to 95 the absence of any obstructive projection and when so engaged the means of connection with the coupling part admits of the heads being freely turned to their ordinary relative positions illustrated in Figs. 1 and 2. 100

The coupling part *c** may be articulated as exemplified in Fig. 11 or it may consist of a piece of chain having the knobs *c c* at its ends as exemplified in Fig. 12.

Referring to Figs. 6, 7 8 and 10 illustrating 105 the collar stud *d d* are the recesses at back of the head part with which in a socket at the junction of the said recesses the knob *e* at the end of the stem *f* is engaged the engagement being similar to that of one of the head parts 110 with the coupling part of the sleeve link already described.

For insertion into a button hole the relative positions of the head and the shank of the collar stud are as illustrated in Figs. 7 and 8 and when the stud is in wear they are 5 as illustrated in Fig. 6.

I claim:—

1. A button like dress fastening comprising a head part having a plurality of recesses in its back extending from the center to the 10 periphery thereof, the bottoms of said recesses being parallel to the general plane of said part and further having in its back a socket at the junction of said recesses partly formed by the material between them and 15 also comprising another part and a spherical knob thereon engaged in said socket, the bottoms of said recesses being distant below the center of the said socket one half the diameter of the stem of the part having the said 20 knob.

2. A sleeve link comprising two head parts each having in its back a plurality of recesses extending from the center to the periphery thereof, the bottoms of said recesses being parallel to the general plane of said parts and 25 further having in its back a socket at the junction of said recesses partly formed by the material between them and also comprising a coupling and spherical knobs on its ends which knobs are respectively engaged 30 in the sockets of the head parts, the bottoms of said recesses also being distant below the center of the said sockets one half the diameter of the part of the coupling intermediate of the end knobs.

ROBERT WORTLEY CLOUGH PALMER.
